UNITED STATES PATENT OFFICE.

GEORGE GOULD GOING, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,242,173.

Specification of Letters Patent.

Patented Oct. 9, 1917.

Application filed March 31, 1916. Serial No. 87,912.

To all whom it may concern:

Be it known that I, GEORGE GOULD GOING, a citizen of the United States, residing at Middletown, in the county of Middlesex and State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and more particularly to structural improvements in devices for carrying the 15 inking ribbon and for insuring its automatic reversal of winding movement.

One of the objects of the invention is the provision of simple and reliable mechanism for insuring and effecting the rewinding of 20 the typewriter ribbon on a spool from which it has been unwound.

A further object is to provide a practical and durable device for guiding and controlling the ribbon intermediate the type carriers and printing point.

Other objects and advantages will be in part obvious and in part noted hereinafter in connection with an embodiment of the invention illustrated in the accompanying 30 drawings.

The invention accordingly consists in the features of construction, combinations of elements and arrangement of parts which will be exemplified in the construction hereinafter set forth, and the scope of the application of which will be indicated in the following claims.

In the drawings,

Figure 1 is a perspective and sectional 40 view of ribbon guiding, winding and reversing mechanism;

Fig. 2 is a partial plan view thereof;

Fig. 3 is an enlarged sectional view on the line X—X of Fig. 2; and

Fig. 4 is a detail perspective view of the ribbon core.

The invention is represented in the drawings as incorporated in a Noiseless typewriter, wherein the traveling carriage is 50 arranged in the rear of the machine and the type carriers are located radially in advance of the platen and mounted for reciprocation to effect printing. Ribbon spools are mounted at opposite sides of the machine frame to 55 wind the inking ribbon from one to the

other through a supporting guide in advance of the platen. It is to be understood, however, that the features of the invention are susceptible of application as well to various other styles of machine.

Referring more particularly to the drawings, there is represented a machine frame having side walls 1 and supporting at the rear part a paper roll 2 and flat metal platen 3 mounted for longitudinal letter space 65 movement and vertical case shifting movement on a guide rail 4. A ribbon cup 5 is arranged on the machine top plate 6 adjacent each side wall in advance of the carriage. Within each ribbon cup is a ribbon 70 supporting disk 7 having a hollow hub 8 to frictionally fit over the split end 9 of a hollow spindle 10 extending vertically adjacent the machine side wall. A ribbon 11 is provided for winding and unwinding from 75 one ribbon cup to the other, and is supported and guided medially in such movement by guides mounted on a holder 12 secured, through the medium of a bracket 13, to the carriage rail 4. These guides are arranged 80 in spaced pairs at the sides of the printing point, and each pair comprises a fixed guide 14 at the upper end of a pin 15 and a pivoted guide 16 on an offset arm 17 of a bracket having a lower arm 18 with down- 85 turned end 19. The pin 15 passes through the arms 17 and 18, so that the guide 16 is pivotally mounted, and it is normally urged to swing away from the platen by a fine spring 20 coiled about the pin 15 and having its ends bearing against a fixed part and the guide. Tensioned movement of the guide 16 is limited by engagement of the offset 90 19 on its lower arm with an extension of the supporting bracket 12. The guides 16, under the influence of the springs 20, 95 serve to take up the slack of the ribbon and hold the same taut away from the printing line in order to render the latter visible. At the same time when the type carriers are actuated to press against the ribbon, the guides yield without appreciable resistance to carry the ribbon against the paper. The ends of the ribbon are secured to cylindrical cores 100 21 designed for ready attachment over the 105 hubs 8 of the ribbon disks 7.

The hollow shafts 10 are designed for alternative clutching with a transversely extending driving shaft 22 geared to a driving shaft 23 of the drum spring 24 which 110

propels the carriage in its letter spacing movement. The connection is such that, during operation, the ribbon is automatically moved to wind on one spool from the other, thereby utilizing the surface uniformly.

- Automatic means is provided to insure a reversal in the direction of movement of the ribbon when unwound from either spool.
- 10 For this purpose each ribbon shaft 10 carries, at its lower end, a stamped gear 25 positioned for mesh with a gear 26 keyed to the driving shaft 22. The latter is mounted for limited longitudinal movement to 15 alternatively mesh with either gear 25 and free the opposite gear, it being understood that only one set of gears can be in mesh at any time, and that when so engaged the corresponding ribbon spool is rotated as the 20 carriage travels in letter spacing direction.
- 20 A cone cam 27 fixed medially to the transverse driving shaft 22 is engaged on its two sides by the V-shaped ends of leaf springs 28 attached to a cross brace 29 of the machine frame so that the shaft is normally 25 held in either of its longitudinal positions.
- 25 A pin or plunger 30 is loosely fitted in each of the hollow ribbon spool shafts 10 and is provided at its upper end with a slot, 30 through which passes the horizontal arm of a bent lever 31 pivoted in the ribbon cup. This connection is such that when the ribbon is coiled about the hub 8, it raises the lever, and accordingly elevates the pin 30 to with- 35 draw the lower end of the latter out of engagement with the shaft 22 therebelow. Similarly, when the ribbon is unwound the lever 31 drops, thereby allowing the pin 30 to lower and carry its end against the shaft 40 22 and into engagement with a cam 33 keyed to said shaft. As rotation of the shaft thereafter continues, said cam rides over the end of the pin and accordingly forces the shaft longitudinally to clutch together the 45 gears 26 and 25 of the respective ribbon spools. Simultaneously the corresponding gears of the other ribbon spool are disengaged. As the ribbon thereafter moves in a reverse direction to coil about the empty 50 spool, the lever 31 is again raised to carry the pin 30 out of engagement with the driving shaft 22; the latter, however, being maintained in its longitudinal position by the pressure of the leaf springs 28.
- 55 The shaft 22 is slidably keyed or splined to a gear 34 held in bracket 35 and meshing with a bevel gear 36 at the end of the drum driving shaft 23. A ratchet clutch is provided in the drum shaft, as shown in Fig. 4, 60 comprising an interior ratchet 37 on the driving shaft and a coil spring 38 on the gear shaft having its outer end pressed against the ratchet teeth, so that only movement of the driving shaft during letter spacing 65 rotates the gear 36.

The transverse shaft 22 is extended through one side wall of the machine frame and is provided with a handle lever 39 by which it may be moved longitudinally to clutch with either ribbon spool for manual 70 rotation. The shaft 22 also has keyed thereon circular V-cams 40, between which normally rests an arm 41 of a bracket 42 fixed for rotation on a short shaft 43 extending through the machine side wall and carrying, 75 adjacent the handle 39, a metal plate 44 with a recess through which the shaft 22 extends. By manual rotation of the plate 44 the bracket arm 41 may be carried to engage the side of either cam 40 to center the 80 shaft 22 and disengage both sets of ribbon spool gears. In this manner the ribbon driving mechanism may be disengaged for stenciling or other purposes.

It is to be noted that the worm or peaked 85 cams 33 keyed to the driving shaft 22 are positioned in relatively opposite directions; that is, the hill of one cam is longitudinally in line with the valley of the other cam. By this arrangement injury is prevented in case 90 the two pins 30 should simultaneously be in lower position, as when the ribbon is removed, in which case the shaft 22 would merely be vibrated longitudinally, when turned.

95 The circular core 21 is designed to be supplied with the ribbons, thereby affording an easy means for mounting the latter on the spools. Each core is provided with an in-turned groove 45 which fits in an opening in 100 the ribbon disk hub 8, whereby these parts are keyed together, and at the same time the groove 45 affords free movement of the lever 31 when elevated as the ribbon is wound.

105 As many changes could be made in the above construction and many apparently widely different embodiments of this invention could be made without departing from the scope thereof, it is intended that all matter contained in the above description or 110 shown in the accompanying drawings shall be interpreted as illustrative and not in a limiting sense.

Having described my invention, what I 115 claim as new and desire to secure by Letters Patent is:

1. In a typewriting machine, in combination, ribbon spools, ribbon shafts therefor, a longitudinally movable driving shaft adapted for selective connection with said ribbon shafts, and means comprising peaked cams on said driving shaft and ribbon controlled means to engage therewith for effecting longitudinal movement of said driving shaft, said cams being keyed to said shaft with 120 their peaks on relatively opposite sides thereof.

2. In a typewriting machine, in combination, a ribbon cup having a slotted hub, ribbon reversing means, including a lever 130

arm adjacent said hub and adapted for control by the ribbon, and a ribbon core to encircle said hub and having a portion to fit the slot of the latter and to receive said lever arm.

3. In a typewriting machine, in combination, a ribbon cup having a slotted hub, ribbon reversing means including a lever arm adjacent said hub and adapted for control by the ribbon, and a ribbon core to

encircle said hub and having an integral indented portion to fit within the slot of the latter and to receive said lever arm when actuated by the ribbon.

In testimony whereof I affix my signature, 15
in the presence of two witnesses.

GEORGE GOULD GOING.
